UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

LATCH

Application filed November 5, 1927. Serial No. 231,225

This invention relates to door or window latches of the kind in which a pivoted latch member is employed, on the door or window, for engaging the stationary strike piece, and in which a rotary knob, on the door or window, is operative to move the latch member about its pivot and out of engagement with the strike piece, when it is desired to open the door or window.

10 Generally stated, the object of the invention is to provide a novel construction and arrangement whereby the said knob and latch member are combined in a structural unit which can be inserted in and fastened to the
15 door or window as a unit, with the latch member in position to operatively engage the said strike piece when the door or window is closed, thus automatically latching the door or window in closed position, and in which
20 the knob and the means for actuating the latch member are disposed in a plane entirely outside of the plane of the door or window, and in which the said latch member is pivoted on a support formed from a sheet-metal blank bent into shape to engage the inner side of the cup-shaped or hollow rose in which the knob is swiveled, said support and rose being permanently secured together.
25

30 It is also an object to provide certain details and features of construction and combinations tending to increase the general efficiency and the desirability of a rotary knob pivoted latch mechanism of this particular character.

35 To the foregoing and other useful ends, the invention consists in the matters herein-after set forth and claimed, and shown in the accompanying drawings, in which,—

40 Fig. 1 is a plan view of a rotary knob pivoted latch mechanism embodying the principles of the invention, showing the door and a portion of the kitchen cupboard in horizontal section.

Fig. 2 is an enlarged vertical section on line 45 2-2 in Fig. 1.

Fig. 3 is a horizontal section on line 3-3 in Fig. 2.

Fig. 4 is a vertical, transverse section on line 4-4 in Fig. 3.

50 As thus illustrated, the invention comprises

a cup-shaped or hollow sheet-metal rose 1, which is applied to the outer side of the door 2, or to a window, and in which the swivel portion 3 of the knob 4 is mounted to oscillate, so that the knob can be partially rotated in either direction. A sheet-metal support 5, approximating a barrel for the latch mechanism, is formed from a sheet-metal blank bent into shape to provide parallel walls 6, and to provide arms 7, which latter are permanently secured to the rose 1 by the hollow rivets 8, as shown. The latch member 9 is disposed between the two parallel wall portions 6 of the support or barrel 5, and is pivoted in position by a pin 10 inserted through the walls 6, as shown. The swivel portion 3 of the knob has a cam 11 fixed thereon and provided with engaging portions 12, as shown. The adjacent end of the latch member 9 is provided with a cross piece 13 fixed thereon, having portions 14 for engaging the cam portions 12 previously mentioned. A coiled spring 15 is disposed in the support or barrel 5 in position to engage the latch member 9, forming a yielding backing for this latch member. A strike piece 16 is fastened to the cupboard wall 17, and is provided with an opening 18 to receive the nose 19 of the latch member 9, when the door 2 is closed, in a manner that will be readily understood.

Rotation of the knob 4 in either direction will, it will be seen, cause one or the other of the portions 12 to co-operate with one or the other of the portions 14 to move or swing the latch member 9 out of engagement with the strike piece. The motion of the latch member and the rotation of the knob are limited by a stop 23 on the support or barrel of the mechanism. The mechanism is held in place by screws (not shown) inserted through the hollow rivets 8 into the door 2, in a manner that will be readily understood, whereby the knob and latch member 9 are incorporated in a structural unit which is attachable and detachable to and from the door as a unit. The inner side of the door may be provided with a metal disk 20 having a slot 21 for the latch member 9, the slot forming a guide for said latch member. Thus the actuating cam 11 and the engaging cross-

piece 13 are not in the plane of the door, but are outside of the door and in the plane of the hollow rose 1, as shown and described. Thus the barrel 5 does not need to fit the 5 hole 22 in the door, being supported entirely by the rose 1, so that this entire latch unit is supported by the door or window through the medium of the rose, the barrel having no direct support on the door or window, but being only indirectly supported thereon through the medium of the said hollow rose, which latter is in the form of a shallow, sheet-metal cup removably fastened with its edges against the outer side of the door or window. 10 This obviates the necessity of boring or cutting a hole which will fit the barrel or latch support.

Without disclaiming anything, and without prejudice to any novelty disclosed, what 20 I claim as my invention is:

1. A rotary knob pivoted latch mechanism comprising a rose, a knob swiveled in said rose, a cam on the swivel of said knob, inside the rose, a support approximating a barrel 25 for the rose, rigidly secured thereto, a pivoted latch member in said barrel, means on said latch member for engaging said cam, whereby said member is movable into unlatching position by rotation of the knob in 30 either direction, said cam and engaging means being in the plane of the rose, and means for detachably securing the rose to the face of a door or window, together with a stationary strike piece for engaging the latch member, and a spring for said latch member, said spring causing said latch member to return the knob to normal position, after the knob is rotated one way or the other, said barrel being formed from sheet metal bent 35 into shape to provide parallel portions between which the latch member is pivoted, and to provide arms through the medium of which the barrel is fastened to the rose.

2. A structure as specified in claim 1, said 45 arms being radial and disposed in the plane of said cam and being permanently fastened to the back of said rose by hollow rivets, with means for spacing said rivets from said door.

3. A structure as specified in claim 1, said 50 barrel having a bent portion forming a stop for said latch member, thereby limiting the rotation of said knob, and said spring being a coil spring disposed behind said stop.

4. A structure as specified in claim 1, said 55 barrel being flattened in the plane of the latch member, and said arms extending at right angles to said plane.

5. In latch mechanism, the combination of a rose, a barrel, hollow rivets permanently 60 securing the rose and barrel together, a rotary knob swiveled in said rose, a latch member pivoted in said barrel, a cam on the swivel of said knob, and means on said latch member to engage said cam, said hollow rivets 65 providing openings through which screws

can be inserted to detachably secure the rose to a door or window, said barrel having radial arms extending in the plane of said cam, through which arms said rivets are inserted.

6. In latch mechanism, the combination of 70 a rose, a barrel, hollow rivets permanently securing the rose and barrel together, a rotary knob swiveled in said rose, a latch member pivoted in said barrel, a cam on the swivel of said knob, and means on said latch member to engage said cam, said hollow rivets providing openings through which screws 75 can be inserted to detachably secure the rose to a door or window, said rose being cup-shaped and provided with an annular inner 80 edge extending a distance beyond the inner ends of said rivets, said edge engaging the door, thus spacing said rivets a distance from the face of the door or window.

7. In latch mechanism, a cup-shaped rose 85 formed from sheet metal, a barrel formed from sheet metal bent into shape to engage the inside surface of the rose, means permanently securing the rose and barrel together, and rotary knob pivoted latch mechanism 90 operatively supported by said rose and barrel, forming a structural unit for attachment to the door or window.

8. In latch mechanism, the combination of 95 an outer casing section, an inner casing section, means to permanently secure the two sections together, precluding separation of the sections, before the mechanism is fastened to the door, a knob swiveled in said outer section, a latch pivoted on said inner section, 100 and a cam rigid with the inner end of the swiveled portion of said knob, said latch member having means for engaging said cam, the axis of the knob and the axis of the latch member being at right angles to each other. 105

9. In latch mechanism, the combination of an outer cup-shaped casing section, an inner sheet-metal casing section provided with projecting feet, means for securing said feet to the inner surface of the outer section, said 110 inner section having flat parallel walls spaced a distance apart, a latch member pivoted between said flat walls, a spring for normally and yieldingly holding said latch member in operative position, a knob swiveled in the outer section, and a cam rigid with the inner end of said knob, said latch member having means for engaging said cam.

Specification signed this 1st day of November, 1927.
